CLAIM

The ornamental design for a combined heating system display and control panel, as shown and described.

DESCRIPTION

FIG. 1 is a perspective view of the combined heating system display and control panel, constructed according to the present invention;

FIG. 2 is a front elevational view of the invention illustrated in FIG. 1;

FIG. 3 is a rear elevational view of the invention illustrated in FIG. 1;

FIG. 4 is a top view of the invention illustrated in FIG. 1; FIG. 5 is a bottom view of the invention illustrated in FIG. 1;

FIG. 6 is a left side elevational view of the invention illustrated in FIG. 1; and,

FIG. 7 is a right side elevational view of the invention illustrated in FIG. 1.

The broken lines are for illustrative purposes only and form no part of the claimed design.
